UNITED STATES PATENT OFFICE.

JOHN MUELLER, OF LISBON, NORTH DAKOTA.

HAY-FORK.

SPECIFICATION forming part of Letters Patent No. 612,527, dated October 18, 1898.

Application filed November 12, 1897. Serial No. 658,316. (No model.)

To all whom it may concern:

Be it known that I, JOHN MUELLER, a citizen of the United States, residing at Lisbon, in the county of Ransom and State of North Dakota, have invented a new and useful Means 5 for Securing Hay-Forks and Like Implements to Handles, of which the following is a specification.

This invention is designed primarily to provide 10 means for securing a hay-fork to its handle so as to admit of the fork being detached from the handle for any desired purpose, and in this connection it is to be understood that the invention is equally well adapted for detachably connecting any style of implement or tool to an operating handle or pole, whereby one handle can be used interchangeably with a number of different implements.

For a full understanding of the merits and 20 advantages of the invention reference is to be had to the accompanying drawings and the following description.

The improvement is susceptible of various changes in the form, proportion, and the 25 minor details of construction without departing from the principle or sacrificing any of the advantages thereof, and to a full disclosure of the invention an adaptation thereof is shown in the accompanying drawings, in 30 which—

Figure 1 is a perspective view of a hay-fork, showing the application of the invention. Fig. 2 is a detail perspective view of the fork and handle separated. Fig. 3 is a detail perspective view of the fastening. Fig. 4 is a 35 transverse section about on the line X X of Fig. 1, looking in the direction of the arrow, showing the parts on a larger scale. Fig. 5 is a detail longitudinal section.

Corresponding and like parts are referred to in the following description and indicated in the several views of the drawings by the same reference characters.

The hay-fork 1 is typical of the variety of 45 implements for which the invention is designed and is provided with a tang 2 of tapering form and wedge-shaped in cross-section, said tang being constructed to interlock with the handle 3, and for this purpose having 50 its inner end expanded, as shown at 4, to fit snugly within a corresponding recess 5 of the handle. A groove or channel 6 is formed

in a side of the handle to snugly receive the tang 2 and is of V form in cross-section.

A ring 7 is formed with an offset or loop 55 portion 8, upon which is fulcrumed a cam-lever 9 to bear against the tang 2 and hold it in its seat or groove 6. This ring is of a size to fit snugly upon the end portion of the handle 3, and the tang is forced into its groove 60 or seat 6 by operating the cam-lever, as will be readily understood. The fulcrum of the cam-lever comes directly opposite the active or bearing end or between said end and the extremity of the lever, whereby the latter is 65 self-locking when its free end is brought against the side of the handle, thereby preventing accidental loosening of the fastening when properly applied. The ring, with the offset or loop portion 8, is made in one piece, 70 and the cam-lever is fulcrumed upon the outer portion of the offset or loop 8 in any manner found most convenient, and, as shown, it is provided with a pair of lips 10, which are bent to encircle the part of the ring upon 75 which the cam-lever is fulcrumed.

In some cases it is preferred to have the expanded terminal 4 of the tang notched, as at 4^a, so as to receive a screw or like headed fastening 11, applied to the handle to assist 80 materially in holding the implement in place and admitting of its easy removal from the handle when required. By having the tang and its seat of wedge form the parts engage frictionally when forced together by means of 85 the fastening, thereby preventing any play or looseness of the implement. Should the handle shrink, the ring can be loosened by moving the free end of the cam-lever away from the handle, and after the ring has been 90 moved upon the handle, so as to prevent any looseness, the parts are secured by bringing the free end of the cam-lever against the handle, as indicated in Fig. 1. In this connection it must be remembered that the lower 95 end of the handle is given a slight taper in the ordinary manner, thereby providing for tightening the ring by moving it upon the lower end of the handle away from the fork or implement.

The tang may be applied to any side of the handle, and the lever 9 will be disposed in any position most convenient, according to the style of implement and kind of handle, so as

to be out of the way. The side members of the loop are strengthened by webs 12 between them and the adjacent portions of the ring.

Having thus described the invention, what is claimed as new is—

- 5 1. The combination with a handle having a longitudinal groove in its side, and having a recess intersecting with the groove, of a hay-fork or like implement having a tang to snugly fit within the said longitudinal groove and having an expanded portion to interlock with the recess and prevent longitudinal movement of the tang, and means encircling the tang and handle to secure the tang in its seat, substantially as described.
- 10 2. The combination with a handle having a longitudinal groove in its side, and having a recess intersecting with the groove, and a headed fastening applied to the recess, of a hay-fork or like implement having a tang to snugly fit within said longitudinal groove and having an expanded portion to interlock with the recess and formed with a notch to receive

the headed fastening and prevent outward and longitudinal movement of the tang, and 25 means encircling the tang and handle to secure the tang in its seat, substantially as specified.

3. In combination, a hay-fork or like implement having a tang of wedge form and its 30 inner end expanded, a handle having a groove or seat in its side to snugly receive the tang and provided with a recess for the reception of the expanded end portion of the said tang, a ring encircling the tang and handle and 35 having an offset or loop portion, and a cam-lever mounted upon the offset or loop portion of the ring, substantially as and for the purpose specified.

In testimony that I claim the foregoing as 40 my own I have hereto affixed my signature in the presence of two witnesses.

JOHN MUELLER.
